UNITED STATES PATENT OFFICE.

CHARLES L. HEISLER, OF SCHENECTADY, NEW YORK, ASSIGNOR TO GENERAL ELECTRIC COMPANY, A CORPORATION OF NEW YORK.

ELECTRIC HEATER.

Application filed September 18, 1923. Serial No. 663,481.

To all whom it may concern:

Be it known that I, CHARLES L. HEISLER, a citizen of the United States, residing at Schenectady, in the county of Schenectady, State of New York, have invented certain new and useful Improvements in Electric Heaters, of which the following is a specification.

My invention relates to electric heaters, more specifically to electric heaters provided with temperature responsive means for controlling the heating circuit, and has for its object the provision of simple, reliable and efficient temperature responsive control means which may be given different temperature settings.

While my invention has application to electrically heated devices in general, it has particular application to electrically heated flat-irons.

In the construction of temperature responsive control means for electric heaters it is essential for the most efficient operation that all lost motion be eliminated between the various parts. This is difficult to effect particularly where the parts are punched or otherwise cheaply formed. Furthermore, in flat-irons for general use it is desirable to have the temperature responsive control device adjustable to maintain different ironing temperatures. A low temperature is desirable for light fabrics, a slightly higher temperature for medium work, and a still higher temperature for heavy goods.

In carrying out my invention, I arrange the various parts so that all lost motion is taken up by a single spring which has the function also of causing quick opening and closing of the control switch for the heating circuit. I have also provided an adjustment whereby the temperature control means may be set to maintain the desired temperature. My invention also comprehends a safety device which is maintained inoperative while the iron is in use but which operates when the iron is not in use to lock the control switch in open position after it has been opened by the thermostat, it being impossible, however, to prevent the opening of the switch under the control of the thermostat.

For a more complete understanding of my invention reference should be had to the accompanying drawings in which Fig. 1

is a section elevation view of a flat-iron provided with temperature control means embodying my invention; Fig. 2 is a plan view with the cover removed of the flat-iron shown in Fig. 1; Fig. 3 is an enlarged view of a portion of the control means; Figs. 4, 5 and 6 are enlarged detail views of the thermostat; while Fig. 7 shows curves illustrating various temperature ranges which may be maintained.

Referring to the drawing, I have shown my invention in one form as applied to the control of an electric flat-iron although it is to be understood that my invention is applicable to the control of various other electrically heated devices. This flat-iron comprises an ironing base 10, which is to be heated, provided with a central cavity 11 in which the temperature control means is mounted, and with a groove 12 extending adjacent its edge in which is clamped a horse-shoe shaped heating element 13 having its terminals 14 and 14^a exposed at the rearward end of the flat-iron base 10. The particular heating unit shown is of the sheath wire type consisting of a metallic sheath 15 in which is a helical resistance conductor 16 embedded in compacted insulating material 17. Preferably the groove 12 is substantially V-shaped, the heating unit having a corresponding shape whereby maximum contact with the sides of the groove is obtained to permit the free conduction of heat therefrom to the body 10. The heating unit is forced into the groove by means of screws 18, 19 and 20 cooperating with a clamping member 21 placed on the heating unit.

To provide for automatic temperature control of the heating unit 13, a thermostat 22 is used. This thermostat comprises a plurality of metallic strips or bars having alternately high and low coefficients of expansion, as shown in Fig. 4. Bars 23 having high coefficients of expansion are made of any suitable material, such as brass, while the bars 24 having low coefficients of expansion are made of a suitable material, such as invar metal. To provide for the necessary tensile strength the bars 23 are made much heavier than the bars 24 due to the much greater strength of the invar metal. The bars 23 are each provided with a longitudinal groove 25 on their upper and lower

sides in which the bars 24 fit. This construction encloses the bars 24 protecting them from oxidation and also exposes the bars 23 so that heat is rapidly conducted to them from the flat-iron body, whereby the bars 23 are made quickly responsive to changes in temperature. In the particular thermostat shown in Fig. 1, seven invar bars 24 are provided and eight brass bars 23, the top and bottom bars being brass. These alternate brass and invar bars are connected at their ends so as to form in effect a single strip folded on itself. The connections between the bars may be made conveniently by providing two pairs of projections 26, 27 and 26^a, 27^a on the respective ends of the bars 24. These projections extend laterally outward from the sides of the bars 24 for a slight distance and then pairs 26 and 27 are turned upward and pairs 26^a and 27^a downward so as to cooperate with notches 28, 29 and 28^a, 29^a formed in corresponding positions in the respective ends of bars 23. As shown in Fig. 4, the inner projections 25 of the bars 24 fit in the notches 28, 29 and 28^a, 29^a respectively while the outer projections of bars 24 fit outside the ends of the bars 23. The construction of the upper and lower bars 23 is slightly different from the intermediate ones. The upper bar 23^a has the longitudinal groove 25 only on its lower side and at its left hand or fixed end is provided with an additional pair of notches 30 and 31. The lower bar 23^b has the slot 25 only on its upper face and has its free end forming the operating end of the thermostat extending a short distance beyond the other bars and provided with a knife-edge bearing 32. This particular method of securing the bars together provides for cheapness of construction and ease of assembly.

The assembled thermostat 22 is enclosed in a casing consisting of a U-shaped clamping member 33 (Fig. 5) which is secured to an upper supporting plate 34. The member 33 is substantially equal in length to the length of the thermostat so that the end of the lower bar 23^b projects somewhat, as shown in Fig. 1. By means of the casing 50 the bars are held in their assembled relation, the casing being sufficiently loose, however, to permit the bars to slide freely therein and with respect to each other.

The upper bars 23^a has its left-hand end secured to the casing. This is effected by providing two pairs of inwardly projecting lugs 35 and 36 (Fig. 6) on clamping member 33 which lugs fit into the notches in the left-hand end of bar 23^a. The lugs 35 and 60 36 may be formed by striking over tongues from the member 33. The thermostat thus assembled is placed in the cavity 11 in the ironing base and is clamped therein in good heat conducting relation with the base by 65 screws 18, 19, 20. Spring washers 37 are

placed between plate 34 and the clamping member 21 to assure the seating of the heating unit in place when the thermostat is seated.

In the operation of the thermostat, upon an increase of temperature, for example, each of the bars 23 will expand and increase in length. Beginning with the top of bar 23^a, it will be observed that the expansion of each bar will be transmitted together with the expansion of the previous bars to the next succeeding bar by means of the connecting bars 24. The movement applied to the end of the thermostat is thus equal to the summation of the expansions of each of the bars 23 less the summation of the expansions of the bars 24. The bars 24 have very nearly a zero expansion coefficient, however, so that the movement applied to the end of the thermostat is substantially equal to the expansion of a rod having a length equal to the sum of the lengths of bars 23. This construction has the advantage of utilizing the relatively great operating force of a bar thermostat in a comparatively short space.

Referring to Fig. 1, the knife-edge bearing end 32 of the thermostat cooperates with a down-turned trigger-shaped member 40 having an intermediate fixed fulcrum 41 carried by member 33 and secured at its upper end to a skeleton arm 42 comprising parallel side bars 42^a and 42^b. The trigger member 40 and arm 42 taken together constitute an operating member 100 having a fixed fulcrum 41. On the right hand end of arm 42 is a bearing rod 43 which is pressed toward the left by a spiral spring 44. The pointed bearing end of rod 43 is seated in a depression in an upright lever 45 having a fixed fulcrum 45^a at its upper end and cooperating at its lower end with the end of a member 46 which extends upwardly for a short distance to a point between the sides of arm 42 and then extends at right angles to the left to a point adjacent the left end of arm 42 where member 46 is provided with a knife-edge end. Cooperating with the left-hand end of arm 42 is a knife blade member 47 which cooperates in turn with one side of a tilting block 48 carrying a skeleton switch arm 49, the opposite side of block 48 resting against the knife-edge end of member 46. As shown in Fig. 3, the knife-blade member 47 is provided at its end with lateral projections 47^a and 47^b between which the tilting block 48 rocks and also with a central projection 47^c which fits between the two sides of arm 42. By means of this construction the member 47 is held in position on arm 42 and the tilting block 48 held in its proper position on the member 47. The member 46 is supported at its left-hand end in a predetermined position by 130

means of a member 50 secured thereto and extending upwardly into screw-threaded engagement with a knob 51 which is rotatably mounted on a support 52 straddling the control mechanism and mounted on the supporting plate 34. By turning knob 51 in one direction or the other it will be observed that the position of the left-hand end of member 46 can be adjusted in a vertical direction. The left-hand end of member 46 is thus fixed in any adjusted position and forms a pivot about which the switch arm 49 may be swung by moving the left-hand end of arm 42 in an upward or downward direction.

A rearwardly extending support 53 is provided as an extension of support 52 on which are mounted insulated stationary contacts 54 and 55 (Fig. 3) in position to operate with bridging contacts 56 and 57 carried by the switch arm 49. The contacts 56 and 57 are insulated from the switch arm but electrically connected to each other. Mounted on support 53 are also terminal pins 58 and 59 (Fig. 2) adapted for a plug connector, pin 58 being connected directly to terminal 14 of the heating unit; while pin 59 is connected through the switch contacts to terminal 14^a. The fixed pivot 45^a also is carried by support 53.

As shown in Fig. 1 of the drawing, the switch arm 49 is in open circuit position caused by lateral movement of the end of the thermostat toward the right due to the occurrence of the predetermined maximum temperature for which the device was set. After the heating circuit has thus been opened the flat-iron will cool off whereby the brass bars 23 of the thermostat will contract causing the free end of the thermostat to move back toward the left. As this movement of the thermostat takes place it will be observed that the left-hand end of the arm 42 will be moved upward slightly, the arm rocking about the fixed fulcrum 41. As this upward movement of arm 42 takes place it will be observed that knife blade member 47 will be tilted about its pivot point on the tilting block 48 to a position of alignment with the direction of the force applied by spring 44, and then moved slightly beyond this position upon the occurrence of a predetermined minimum temperature, when spring 44 will be in a direction to move the tilting block downward in a counter-clockwise direction as viewed in Fig. 1 about its pivot on the end of member 46, thus throwing the switch arm 49 upward and closing the circuit for the heating unit. As the flat-iron now heats up, arm 42 will be tilted downward due to the elongation of the thermostat whereby upon the occurrence of a predetermined maximum temperature the switch arm will be snapped downward to open position as

shown in the drawing. The heating circuit is thus automatically opened and closed in response to the temperature of the flat-iron so as to maintain the temperature within a predetermined range determined by the minimum and maximum temperature limits at which the device operates.

In order to regulate the temperature which will be maintained, button 51 is turned in one direction or the other. For example, to increase the temperature, button 51 will be turned in such direction as to raise the left-hand end of member 46, this being effected through the screw connection with the supporting member 50. To lower the temperature, button 51 is turned in such direction as to lower the end of member 46. By means of this adjustment the flat-iron can be set to maintain any one of the temperature cycles indicated in Fig. 6. For light fabrics the control mechanism will be set to maintain a temperature range substantially between 420 and 480 deg. F. as shown by the curve 60; for medium work the temperature range will be substantially between 460 and 540 deg. F. as indicated by curve 61; while for heavy work a temperature range of substantially between 520 and 580 deg. F. will be maintained as indicated by curve 62.

For the purpose of giving the switch arm 49 a more positive kick-off or movement from one position to the other, a screw pin 63 is secured to arm 42 near its outer end. This pin extends freely through an aperture 64 in member 46 and is provided with two spaced flanges 63^a and 63^b between which the switch arm moves. It will be observed that the pin extends through a slot in the switch arm so that it is embraced by the two sides of the switch arm. Upon movement of arm 42 in an upward direction the lower flange 63^b will engage the switch arm at the kick-off point tending to positively start it upward, and upon movement of arm 42 downward the upper flange 63^a will positively start the switch arm downward.

A cover 65 and a handle 66 are provided for the flat-iron. These parts are secured to each other and to the ironing base 10 by means of an extension of screw 18 and a screw 67 connecting with support 34. A plug guard and heel rest 68 is also provided. This member 68 also serves as an additional protecting means for the control mechanism.

For the purpose of preventing the heating of the iron when not in use in the event that it is inadvertently left connected to the electrical supply circuit, I have provided latching means for the switch which is operated by a thumb rest button 69. The button 69 is secured to a lever arm 70 pivoted to the handle at a point 71. The lower end of this lever arm extends through an elongated slot 72 in the handle 66 so that the lever arm 70 is held in a position to maintain the switch arm 49 in the open position as shown in Fig. 1.

gated opening 72 in the cover into the interior of the flat-iron where it engages with a horizontal lever arm 73 (Fig. 3) pivoted at 74 to the supporting plate 34. On the right-hand end of lever 73 is a laterally extending latching projection 73^a which extends above arm 42 without interfering with its movement and is arranged to slip over switch arm 49, as shown in Fig. 1, when the arm is in its lowermost or open circuit position. The lever 70 is biased about its pivot by a spiral spring 75 so as to tend to move the latching projection 73^a inward over the switch arm. In the operation of this latching device, while the iron is in use, the operator will unconsciously depress button 69 with his thumb and thus maintain latch 73^a in the position shown in Fig. 3 such that it will not interfere with the circuit closing movement of the switch arm. In case, however, the iron is put aside without disconnecting it from the heating circuit, then latch 73^a will be forced by spring 75 upon releasing thumb rest 69 into engagement with the side of the switch arm and when the switch arm is moved downward by the thermostat to open the heating circuit upon the occurrence of the predetermined maximum temperature, the latch will slip over the switch arm and secure it in open circuit position. As the iron cools down thereafter, it will thus be impossible for the heating circuit to be again closed. Upon resuming work or upon lifting the iron preparatory to resuming work, the operator will without conscious effort depress thumb rest 69 whereby the switch arm is released and thereupon is moved upward closing the heating circuit. The inner end of latch 73^a is made square so that it is impossible for it to slip under the switch arm or in any way oppose the movement of the switch arm downward to open circuit position under the control of the thermostat. When the thumb rest is released with the switch closed the inner squared end of the latch comes to rest against the side of the switch arm but does not interfere with its downward movement to open position.

It will be observed that the various parts of the control mechanism are secured to their supports, fixed fulcrums 41 and 45^a, and in their proper cooperating relation with each other and with the thermostat by means of the spring 44. The spring therefore takes up all lost motion so that the control device is immediately responsive to movement of the thermostat. In fact, to take the control device apart, it is necessary only to release the spring 44 when the parts will be released. This construction makes it possible to use stamped or otherwise cheaply formed parts and facilitates the assembly of the parts.

While I have described my invention as

embodied in concrete form and as operating in a specific manner in accordance with the provisions of the patent statutes, it should be understood that I do not limit my invention thereto, since various modifications thereof will suggest themselves to those skilled in the art without departing from the spirit of my invention, the scope of which is set forth in the annexed claims.

What I claim as new and desire to secure by Letters Patent of the United States, is:

1. Thermostatic control means for electric heaters and the like, comprising a thermostat, circuit control means, a plurality of members forming an operating connection between said control means and said thermostat, and a common means for holding said members in their various cooperating relations and for moving said control means from one position to another upon movement of said thermostat.

2. Thermostatic control means for electric heaters and the like, comprising a thermostat, circuit control means, a plurality of members forming an operating connection between said control means and said thermostat, stationary supports forming fulcrums for said members, and a spring for holding said members on said supports in their various cooperating relations and for moving said control means from one position to another upon movement of said thermostat.

3. Thermostatic control means for electric heaters and the like, comprising a thermostat, a control switch, a member having a fixed fulcrum and pivotally cooperating with said switch and said thermostat, a second member having a fixed fulcrum and pivotally cooperating with said first member, a third member pivotally cooperating with said second member and said switch, and a spring carried by said first member forming a part of the pivotal connection with said second member acting to hold said members on their fulcrums in their various cooperating relations and to snap said switch from one position to another upon movement of said thermostat.

4. Thermostatic control means for electric heaters and the like comprising a thermostat, a tilting block, a switch arm carried by said tilting block, a member having a fixed fulcrum and pivotally cooperating with said tilting block and said thermostat, a second member having a fixed fulcrum and pivotally cooperating with said first member, a third member pivotally cooperating with said second member and said tilting block, and a spring carried by said first member forming a part of the pivotal connection with said second member acting to hold said members on their fulcrums in their various cooperating relations and to snap said switch arm from one position to another

- upon movement of said thermostat.
5. Thermostatic control means for electric heaters and the like, comprising a thermostat, circuit control means, a plurality of members forming an operating connection between said control means and said thermostat, a common means for holding said members in their various cooperating relations and for moving said control means from one position to another upon movement of said thermostat to maintain a predetermined temperature, and means for adjusting one of said members to regulate said temperature.
15. Thermostatic control means for electric heaters and the like, comprising a thermostat, an adjustable member, a switch arm pivoted on said adjustable member, and a second member cooperating with said thermostat and acting on said switch arm to move it about its pivot to open and close the heater circuit, and means for adjusting said adjustable member to change the temperature setting.
25. Thermostatic control means for electric heaters and the like, comprising a thermostat, a member having a fixed fulcrum actuated by said thermostat, a second member having a fixed fulcrum and pivotally operating with said first member, a third member pivotally cooperating with said second member, a switch arm pivoted on said third member and moved about its pivot by said first member upon movement of said thermostat to open and close the heater circuit, and means for adjusting said third member to change the temperature setting.
35. Thermostatic control means for electric heaters and the like, comprising a thermostat, a member having a fixed fulcrum actuated by said thermostat, a second member having a fixed fulcrum and pivotally cooperating with said first member, a third member pivotally cooperating at one end with said second member, a tilting block pivoted on the other end of said third member and moved about its pivot by said first member upon movement of said thermostat, a switch arm carried by said tilting block, and means for adjusting said third member to change the position of the pivot of said tilting block.
45. Thermostatic control means for electric heaters comprising circuit control means, a thermostat for operating said control means so as to maintain a substantially constant temperature, and manually controlled means for interrupting the control of said control means by said thermostat.
55. Thermostatic control means for electric flat-irons and the like, comprising thermostatic means for automatically opening and closing the circuit thereof to maintain a substantially constant temperature, and manually controlled means for holding the circuit open when it has been opened by said thermostatic means.
11. Thermostatic control means for electric flat-irons and the like, comprising control means for the heating circuit thereof, thermostatic means associated with said control means so as to automatically open and close said circuit to maintain a substantially constant temperature, and manually controlled means operative when the flat-iron is released for holding said control means in open circuit position after said control means has been opened by said thermostatic means.
12. Thermostatic control means for electric heaters, comprising circuit control means, a thermostat connected to operate said control means so as to open and close the circuit of the heater and maintain a substantially constant temperature and releasable latching means for holding said control means in open circuit position.
13. Thermostatic control means for electric flat-irons and the like, comprising a control switch, a thermostat for opening and closing said switch, and means for latching said switch in open position, said latching means being maintained inoperative while the iron is in use.
14. Thermostatic control means for electric flat-irons and the like, comprising a control switch, a thermostat for opening and closing said switch, and manually controlled means for holding said switch open after it has been opened by said thermostat.
15. Thermostatic control means for electric flat-irons and the like, comprising a control switch, a thermostat for opening and closing said switch, and manually controlled means operative while the iron is not in use to prevent closing of said switch, but maintained ineffective while the iron is in use whereby said switch is controlled by said thermostat to maintain a predetermined temperature.
16. Thermostatic control means for electric flat-irons and the like, comprising a control switch, a thermostat for opening and closing said switch, and latching means held inoperative without conscious effort of the operator while the iron is in use, but when released preventing reclosing of said switch after it has been opened by said thermostat.
17. Thermostatic control means for electric flat-irons and the like, comprising control means for the heating circuit thereof, thermostatic means associated with said control means so as to automatically open and close said circuit to maintain a substantially constant temperature, latching means for holding said control means in open circuit position after said control means has been opened by said thermostat, and a

thumb rest operatively connected to render said latching means ineffective when depressed.

18. Thermostatic control means for electric flat-irons and the like, comprising a thermostat, a control switch opened and closed by said thermostat, latching means biased to normally prevent closing of said switch, and a thumb rest operatively connected to said latching means whereby said latching means may be moved to allow said switch to close by depressing said thumb rest.

19. Thermostatic control means for electric flat-irons and the like, comprising a thermostat, a control switch opened and closed by said thermostat, latching means biased to normally prevent closing of said switch, and releasing means for said latch-

ing means actuated when the iron is in use 20 to hold said latching means in inoperative position.

20. Thermostatic control means for electric flat-irons and the like, comprising a thermostat, a control switch opened and closed by said thermostat, latching means for holding said switch in closed position, a thumb rest pivotally mounted on said iron, an operating connection between said thumb rest and said latching means, and a spring 25 30 for biasing said thumb rest to move said latching means in position to lock said switch after it has been opened by said thermostat.

In witness whereof, I have hereunto set 35 my hand this 17th day of September, 1923.

CHARLES L. HEISLER.
